ELECTRICAL APPARATUS

Martin Neuner, Fairview, N. J., assignor to Béndix
 Aviation Corporation, South Bend, Ind., a corporation of Delaware

Application February 7, 1941, Serial No. 377,918

1 Claim. (Cl. 200—87)

This invention relates to electrical apparatus, and particularly to electro-magnetic circuit controllers.

An object of the invention is to provide a novel method of assuring uniform contact action as between the stationary and movable elements of circuit make-and-break devices actuated by electro-magnetic means.

A further object is to provide circuit controlling mechanisms of novel construction.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claim for this purpose.

In the drawing:

Figs. 1, 2 and 3 are perspective and elevation views of a device embodying the invention; and

Fig. 4 is a wiring diagram of circuits to which the novel circuit-controlling mechanism is applicable in the manner indicated.

In the drawing an L-shaped bracket 51 is shown as disposed with its longer leg in horizontal position, to receive the core 56 of an electromagnet having a heavy wire 57 wound thereon to form a single coil source of excitation of the magnetic circuit, of which the bracket 51, the core 56, and the armature 61 constitute major component parts. Armature 61 is pivotally mounted on the vertical leg of bracket 51, and carries a counter-weight 99, beneath which is suspended a tensioning spring whose pull is adjustable by the turning of a screw 102 mounted in bracket 101. This bracket 101 has a detent 103 engageable with a notched wheel 104 forming part of the adjusting screw assembly, the detent thus serving to lock the screw in adjusted position.

The novel circuit-controlling mechanism includes contact elements carried by the armature 61 on opposite sides of the bracket 51; one being carried on the under surface of the armature, adjacent counter-weight 99, and the other being in the form of a triangular prism 81 having a shank 82 apertured to receive a suspension bar 83 integrated with, and extending outwardly from, the central portion 86 of the armature assembly, and thus indirectly carried by the armature 61; the bar 83 having no surface contact with armature member 86. A sleeve 84 of in-

sulating material surrounds the bar 83, and is retained by metal cap 85, having a forced fit thereon. The contact element first referred to is designated by reference character 87 and its complementary contact element by reference character 88; the latter being integrated with a screw 89 extending down through threaded openings in guide-piece 91, and having a head and nut 92 at its lower end to adjust the contact action. The guide-piece 91 is insulated from bracket 51, as is also the conductor terminal 93, from which terminal connection is made to the pilot light L (Fig. 3).

The novel circuit-controlling mechanism further includes a pair of outwardly flaring contact plates 106, 107 with vertical portions held to spacer plate 108 of insulating material by bolts 109 (which bolts also clamp the insulating plates 110, 111 to the assembly) and with horizontal portions held flush against insulating bed-plate 112 by suitable bolts 114, 115, which bolts also act as conductor terminals for the wires 116, 117 (see Fig. 3).

With the construction indicated absolute accuracy and perfection in switch assembly and operation are assured, as the plates 106, 107 can be formed in a jig-fixture so as to be uniform in length, width and angularity; and the wedge 81 is free to swing to offset any imperfection in 30 the armature construction or assembly.

When the invention is applied to the control of a battery-generator combination, as shown in Fig. 3, it will function as follows:

When generator G is first started the flow of 35 current through winding 57 will not be sufficiently heavy to attract armature 61 against the opposing force of counter-weight 99, and therefore the current will pass to the battery B (or load) by way of rectifier R. The subsequent rise in current strength will increase the magnetic strength through core 56 and draw wedge 81 into contact with plates 106, 107, thereby closing a by-pass circuit, around the rectifier R, to the battery and load. At the same time the withdrawal of contact 87 from contact 88 will extinguish the pilot light L, signifying that battery-charging is now in progress. The subsequent slowing down or stopping of the generator 50 will allow weight 99 to reopen the switch 106, 107, and re-close switch 87, 88, to re-light the pilot L; but no reverse flow from the battery to the generator will occur, as the rectifier R is unidirectional in its action. The re-lighting of 55 pilot L warns the attendant that battery charg-

ing has ceased, and that the generator is not producing its normal amount of power.

By the combination shown there is eliminated any need of a second winding on the relay 57, with its resultant tendency to produce more or less constant vibration of the armature. Hence the contacts will remain firmly engaged for relatively long periods, and excessive wear, as well as erratic make-and-break action, avoided.

What is claimed is:

In a magnetic switch, a pair of angularly disposed contacts, an armature having a cylindrical extension, a triangular prism of current con-

ducting material, said prism having an apertured shank to receive said cylindrical armature extension, wherefore said armature extension constitutes the sole mounting for said prism, and upon which extension said prism is freely suspended for pivotal movement about the axis of said armature extension, current responsive means for causing said armature to move said prism into engagement with said angularly disposed contacts, and means for preventing any lateral shifting of said prism independently of rotation thereof about said armature extension axis.

MARTIN NEUNER.
